LOADING MACHINE

Edwin B. Royle, Salt Lake City, Utah, assignor to
The Eimco Corporation, Salt Lake City, Utah

Application May 28, 1937, Serial No. 145,291

6 Claims. (Cl. 214—132)

My present invention relates to improvements in loading machines or muckers of the type employing a vertically swinging shovel, which is also oscillatable horizontally on a vertical axis 5 in order that digging or loading operations of the shovel may be accomplished laterally of the machine. The invention is particularly related to the means for centering the loaded shovel or dipper, after a lateral digging operation, in order 10 that the shovel may be aligned with a car when the loaded shovel is in dumping position. The subject matter of the present invention is an improvement on the appliances illustrated in patents of Finlay et al. Nos. 1,906,000 and 1,906,001 15 of April 25, 1933.

The invention is preferably embodied in a self-contained loading machine mounted upon a wheeled-truck or carriage; the vertically swinging shovel and a rolling support therefor are mounted upon a pivoted superstructure that is capable of being oscillated or swung horizontally 20 on a vertical axis to bring the shovel to either side of a railway track; and co-acting means on the horizontally oscillatable superstructure and the carriage are employed to center the laterally disposed shovel. The loading machine is especially adapted for use in mines where a large proportion of the material to be handled or loaded lies at the opposite sides of the railway track. 25 Because of the compact arrangement of parts and of the minimum size of the machine in which the invention is embodied, the empty shovel may with facility be swung by hand to either side of the track or railway for filling or digging operations, and then the loaded shovel may readily 30 be swung back into alignment with the wheeled truck and automatically centered with relation to the truck by the use of power operated means in connection with the vertically swinging movement of the filled or loaded shovel. The self-contained loading machine is equipped with a suitable motor for propulsion, and also for operating its various parts, and the overhead-swinging shovel is designed to dump its load into a car coupled directly at the rear of the machine. 35

By the utilization of the centering means of my invention in the loading machine the dipper or shovel may be manipulated for digging, in a lateral position, before the centering movement occurs, then, after the shovel is filled the superstructure and shovel are automatically centered with relation to the carriage during the travel of the loaded shovel from a loaded position to 40 dumping position, and means are provided for

holding these parts in alignment while the load is being discharged from the shovel.

The parts of the machine, including the centering means, are compactly arranged to occupy a minimum of space and to protect them from 5 wear and breakage; the construction of parts is simplified to insure durability, and the operations of the machine are accomplished with facility and reliability.

The invention consists in certain novel combinations and arrangements of parts as will hereinafter be more fully pointed out and claimed. In the accompanying drawings I have illustrated one complete example of the physical embodiment of my invention wherein the parts are combined and arranged according to one mode I have devised for the practical application of the principles of my invention. 10 15

Figure 1 is a view in side elevation, with parts broken away for convenience of illustration, of 20 a loading machine embodying my invention, with the shovel and its rocker arms in loading position, and disclosing a motor and parts operated thereby.

Figure 2 is an enlarged, detail, vertical, transverse sectional view through the housing and showing the rotary cam-drum of the centering means. 25

Figure 3 is a view in side elevation showing the loading machine and part of a mine car on the 30 railway track, with the rocker arms and shovel in loading position; and in dotted lines the rocker arms and shovel are shown in successive positions; and the accompanying movements of the centering means are also shown by dotted lines. 35

Figure 4 is a transverse view, partly broken away, showing the relation of the rotary cam-drum to the friction-roller or cam roller having a stationary support on the wheeled truck or carriage of the machine. 40

Figure 5 is a plan view showing the superstructure, rocker arms and shovel swung to a left-hand position with relation to the carriage and railway, and by dotted lines indicating these parts swung to the right-hand side of the railway. 45

In order that the general arrangement and utility of the various parts may readily be understood I have shown in Figure 3 a portion of a mine-car M coupled at the rear of the machine, 50 which machine includes a truck 1 with wheels 2 rolling on the rails 3, and the machine is self-propelled through rigging not shown but enclosed within the truck 1. The rigid bed-plate 4 forming the deck of the truck and provided 55

with rounded ends is equipped with a center pin 5, dotted lines in Figure 5, and an oscillatable superstructure is pivoted on this vertical axis to swing horizontally. The superstructure includes 5 a table or horizontal base plate 6 with rigid, upright side walls 7 and 8, and in Figure 5, by dotted lines, a circular track for ball bearings is indicated at 9 between the wheeled truck and the superstructure, to support the latter.

10 In Figure 1 where the shovel is shown in loading position, it will be seen that the shovel or dipper is rigidly attached to and supported upon two laterally spaced rocker arms 11 and 12 which have rounded or curved contact faces or edges 15 that roll on or are guided by longitudinally extending rails 13, 13 rigid with the base plate 6 and located within the side walls 7 and 8 of the superstructure. The rolling movement of the arms is indicated in Figure 3, as the successive 20 positions of the shovel and arms are indicated from loading position to dumping position or vice versa.

By means of the rocker arms the shovel is 25 swung upwardly and rearwardly from loaded position to dumping position, and to stop the shovel at the end of its dumping movement I provide bumper springs 14, 14 mounted upon a cross bar 15 attached at its ends to the two side walls 7 and 8, and the rocker arms have laterally extending 30 stop plates 16 in position to contact with the springs at the end of the travel of the shovel. By impact of the plates with the springs the swinging movement of the shovel is stopped, and by inertia the load is projected and dumped into 35 the car M.

For swinging the arms and the shovel I employ a reversible air motor 17 mounted on the superstructure, which drives a rotary drum 18, and a chain 19 mounted upon the drum has its outer 40 end anchored to a cross bar 20 which rigidly joins the rocker arms 11 and 12. To insure the necessary leverage, the chain passes over a guide pulley 21 journaled in the upper end of a bracket 22 mounted on the superstructure between the 45 winding drum 18 and the rocker arms.

In Figure 1 connections are shown at 23 and 24 from the air motor 17, which are extended to 50 propulsion mechanism for the wheeled truck, and it will be understood that the machine is propelled to project the shovel as far as possible into a muck pile, and then, if the motor 17 is operated and controlled to actuate the shovel (through the winding drum and chain) the rocker arms 55 impart successive digging movements to the shovel, until it is filled, and the shovel is then emptied as above described.

Power from the motor 17 having been cut off just prior to stopping the swing of the shovel, the recoil of the springs 14 from the impact, 60 initiates the forward swing of the shovel under action of gravity, and the shovel is thus returned to digging or loading position.

As above described, the shovel is adapted to 65 operate directly in front of the loading machine as in Figure 1, or at either side of the railway as in Figure 5. For lateral operations as in Figure 5, the shovel is swung by hand, out of alignment with the truck, the superstructure and shovel assembly of course moving with the shovel. For 70 dumping operations, the laterally disposed shovel is aligned with the longitudinal axis of the truck and railway, through co-acting means on the superstructure and truck, the operation of these coacting means being initiated and accomplished 75 through the swinging movement of the shovel

and rocker arms, under power from the motor.

For this purpose a centering roller 23 is journaled upon a stationary or fixed bearing or axis 24 at the longitudinal center of the wheeled truck, and preferably forward of the pivot 5 of the 5 superstructure, and a rotary cam-drum 25 is mounted transversely of the superstructure, above the roller and for co-action therewith.

As best seen in Figure 2 the cam drum is a 10 hollow, integral, metal cylinder, having its two heads 26, 26, truncated and arranged in planes disposed on converging lines, thus shaping the drum to facilitate its installation in the enclosure formed by the housing 27 and its cap or end plate 28. The housing, which is mounted on the 15 top of the plate 6 of the superstructure, extends transversely thereof and is limited as to its length because of the restricted width of the machine, and this specific shape of the cam-drum insures a maximum length to the drum to accommodate 20 the required cams and afford a wide bearing face for the cams, which are indicated as 29 and 30. These peripheral cam edges are formed by providing an opening in the cylindrical wall of the drum, from end to end, and the cam edges curve 25 toward the longitudinal center of the drum, and merge into spaced parallel annular walls 31, 31 which terminate in a notch or recess 32 at the center of the drum and of slightly larger dimensions than the cam roller 23 mounted on the 30 wheeled truck. As best seen in Figure 4 the two cam edges 29 and 30, at their outer ends terminate in parallel annular walls 33 and 34, and these annular edges or walls of the opening in the drum terminate at the longitudinally extending 35 wall 35 of the cam opening.

The opposite ends of the cam-drum are fashioned with centrally aligned bearing bosses 36 and 37, extending both inwardly and outwardly of the drum-heads, and one end of the drum is 40 provided with a trunnion 38 journaled in a bearing seat 39 of the removable cap plate 28. The other end of the drum is fixed on a stud shaft 40 that is journaled in a bearing 41 of the housing, and the inner end of this stud shaft, which passes 45 through the boss 37, is threaded to receive a retaining nut 42, which holds the drum rigid with the shaft.

The shaft may be rocked in its bearings and the cam drum may be oscillated, or partially 50 turned on its trunnions and longitudinal axis in either direction by movement imparted thereto from one of the rocker arms to a lever 43 which is rigid with the stud shaft, through a link 44 that is pivoted at 45 to the lever and at 46 to the 55 rocker arm.

As seen in Figure 5, and because of the annular edges 33 and 34 of the cam drum, it will be apparent that while the shovel is turned to a lateral position, the shovel may be lifted, as in 60 filling or loading strokes, without operating the centering means, for the reason that one of these parallel edges 33 or 34 will glide past the roller 23 without a cam-action.

After the shovel has been filled or loaded, and 65 after its initial lifting movement, one of the cam edges 29 or 30, by its contact with the cam roller, starts to swing the super-structure with the travel or upwardly and rearwardly swing of the shovel, and the superstructure and shovel are centered 70 just before the shovel is dumped. As the cam drum revolves and the parallel walls 31, 31 contact with the cam roller, this contact stops the lateral swing of the superstructure, and the thus centered and retained superstructure and shovel are in 75

position for the shovel to dump its contents into the mine car M.

Due to the recoil of springs 14, the gravity-return movement of the rocker arms and shovel is initiated, and the shovel returns to digging position alined with the carriage or truck, free from the influence of the centering devices, and in this position the shovel may be operated, and the rotary cam-drum may revolve or partially revolve without operation of the centering means.

If, however, the shovel is to work in a lateral position, it may be swung laterally, by hand, after the recessed portion 31-32 of the cam drum has rolled out of engagement with the cam-roller and while the shovel is being returned to digging position.

The co-operation of the link and lever connection between the rocker arm and the centering drum is illustrated by the several positions of these parts in Figure 3, and it will be understood that the swinging movement of the rocker arm partially revolves the drum in one direction as it moves from loaded to dumping position, and then partially revolves the drum in the opposite direction as it swings from dumping to filling position.

The linkage employed in driving or revolving the centering drum 25, it will be seen, is arranged so that the link 44 and lever 43 are related to the rocker arms in such manner as to allow the rocker and shovel assembly to be raised from filling or down position of Figure 3 to the dotted loaded position before initial movement of the drum, and therefore without causing any appreciable rotation or action of the drum against its centering roller. Under these conditions, and in some instances, the parallel annular guide walls 33 and 34 of the drum are not called on to perform their functions.

With the shovel engaged in lateral digging operations, as the shovel and rocker assembly are moved from (dotted) loaded position to the centered position, link 44 swings lever 43 through the distance of the arc B, thereby causing the centering drum to revolve or rotate with one of its cam edges (29 or 30) frictionally engaged with roller 28, and by the co-action of this cam edge and the roller the superstructure is moved into alinement with the under carriage. Continued rocking movement of the arms and overhead swing of the shovel to the dumping position swings link 44 and lever 43 through the distance of arc C, which movement in turn revolves the drum and places the parallel edges or surfaces 31-32 in straddling relation to the roller 28, and the co-action of these elements holds the superstructure in alinement with the carriage.

Having thus fully described my invention, what I claim as new and desire to secure by Letters Patent is:

1. In a loading machine, the combination with a support, a horizontally oscillatable superstructure, a vertically swinging shovel mounted on the superstructure, and means for swinging the shovel, of a central cam member mounted on the support, a rotary drum mounted transversely of

the superstructure having a cam-edge, and power transmitting means between the shovel swinging means and said rotary drum.

2. In a loading machine, the combination with a carriage, a horizontally oscillatable superstructure mounted on the carriage, a central cam-member mounted on the carriage, a vertically swinging shovel mounted on the superstructure, and means for swinging the shovel, of a rotary cam-device mounted transversely of the superstructure for co-action with said cam-member, and power transmitting means between the shovel swinging means and said rotary drum.

3. In a loading machine, the combination with a carriage having a central cam member, a horizontally oscillatable superstructure mounted on the carriage, a vertically swinging shovel mounted on the superstructure, and means for swinging the shovel, of a rotary cam-device mounted on the superstructure for co-action with the cam-member to center the superstructure, power transmitting means between the shovel swinging means and said rotary drum, and means for holding the superstructure in centered position while the shovel is in dumping position.

4. In a loading machine, the combination with a carriage having a central cam-roller, a horizontally oscillatable superstructure mounted on the carriage, a vertically swinging shovel mounted on the superstructure, and means for swinging the shovel, of a rotary drum mounted transversely on the superstructure and a cam-surface on said drum for co-action with the roller in centering the superstructure, and an annular surface on the drum for co-action with the roller to hold the superstructure centered while the shovel is in dumping position.

5. In a loading machine, the combination with a carriage having a central cam roller, a horizontally oscillatable superstructure mounted on the carriage, a vertically swinging shovel mounted on the superstructure, and means for swinging the shovel, of a rotary drum mounted transversely of the superstructure and having a rigid lever-arm, a link connecting said arm with the shovel swinging means, said drum having a peripheral opening in its wall comprising a central recess with parallel edges, cam-edges diverging from said parallel edges and merging with spaced annular edges adjacent the ends of the drum, and a transversely extending edge joining said annular edges.

6. In a loading machine, the combination with a carriage having a central cam-roller, a horizontally oscillatable superstructure mounted on the carriage and a housing on the superstructure, a rotary drum having end-heads disposed in planes located on diverging lines, trunnions on said end-heads journaled in the housing, cam devices on the drum for co-action with the cam-roller, a vertically swinging shovel mounted on the superstructure and operating means therefor, and power transmitting means between said operating means and said drum.

EDWIN B. ROYLE.
